VACUUM BREAKER FOR FLUSHOMETERS

Daniel A. Gillen, Flushing, N. Y.

Application February 9, 1939, Serial No. 255,442

6 Claims. (Cl. 137—69)

This invention relates to vacuum breakers for flushometers, and has for an object to provide a construction which may be used in the tail-piece of the flushometer or in the flushometer itself.

Another object is to provide a construction which will automatically function to break any vacuum in the stand pipe supplying water to a flushometer.

10 A further object of the invention is to provide a vacuum breaker which is used in connection with flushometers and which automatically closes when the water is passing through the flushometer and automatically opens after the water has 15 passed.

An additional and more specific object of the invention is to provide a vacuum breaker which may be applied to the flushometer itself or to any pipe between the flushometer and the flush bowl 20 with the structure so formed as to quickly close as the water flows and quickly open after the water has passed so as to immediately provide air from a point exterior of the flushometer to a point interior thereof, thus presenting an automatic means for supplying air through the flushometer to the stand pipe whenever the flushometer is opened by suction from the stand pipe.

In the accompanying drawing—

Fig. 1 is a perspective view of a flushometer, 30 toilet bowl, and associated parts, together with a vacuum breaker embodying the invention;

Fig. 2 is an enlarged view partly in elevation and partly in section illustrating an embodiment of the vacuum breaker in the flushometer tail-piece;

Fig. 3 is a sectional view through Fig. 2 approximately on the line 3—3;

Fig. 4 is a view partly in section and partly in elevation of a flushometer and illustrating the 40 invention applied directly to the flushometer.

In large buildings and elsewhere a stand pipe or water supply pipe is provided for supplying water to the toilets, wash bowls, etc. in the buildings. In most buildings at present there is provided a valve 1 which is known as a flushometer because when it is operated it will flush the toilet bowl and allow a certain amount of water to pass and then automatically close. As long as the stand pipe or water supply pipe to the 50 flushometer is provided with water under pressure, the flushometer will remain closed unless opened manually. However, sometimes where there is a fire or for some other cause, a stand pipe in a building is deprived of water and as the 55 water recedes in the stand pipe a certain amount

of rarefaction will be produced and this rarefaction or suction will cause the various flushometers in the building to open and allow air to pass from the various toilet bowls into the stand pipe. If any of the toilet bowls are contaminated, germs will pass in the air and will contaminate the stand pipe so that when water is again supplied the water will be contaminated. These stand pipes are not only connected with flush bowls but with wash basins and even with valves 10 from which drinking water is drawn.

To obviate the entrance of germs from foul flush bowls, the vacuum breaker embodying the invention has been provided and arranged as shown in the accompanying drawing, so that 15 immediately upon the slightest opening of the flushometer 1, by reason of rarefaction in the stand pipe, clean air from the room will pass into the stand pipe. If the entire building is provided with devices embodying the invention, 20 these devices will automatically function as the water lowers from floor to floor. If there should be fifteen flushometers on a given floor, there would be fifteen vacuum breakers and, consequently, fresh air from the room will be supplied 25 to the stand pipe through fifteen vacuum breakers, whereby little or none of the foul air from the bowls can enter the stand pipe. This eliminates or reduces to a minimum the chances of germs entering the stand pipe and spreading disease germs to the drinking water or washing water.

As illustrated in Figs. 1 to 3, the vacuum breaker 2, which embodies the invention, is shown applied to the flushometer tail-piece 3, which is 35 nothing more than a tube having a flange 4 clamped to the flushometer 1 by a suitable nut 5. In applying the vacuum breaker 2, it is only necessary to drill two holes, namely, holes 6 and 7, and then place the vacuum breaker in position. The vacuum breaker 2 is formed with what may be termed a body 9, which is really a T-shaped tubular structure having a threaded opening 10 discharging into the passageway 11, which in turn discharges into passageways 12 40 and 13, which latter passageways are enlarged.

The passageways 12 and 13 are formed by what may be termed tubular extensions 14 and 15. Thimbles or hollow bushings 16 and 17 are fitted into these tubular extensions and have heads 50 18 and 19 pressed against the outer surface of the tail-piece 3. As clearly illustrated in Fig. 2, each of these thimbles has a passageway 20 extending entirely therethrough and discharging into the chambers or passageways 12 and 13. In 55

constructing the device the thimbles or bushings 16 and 17 are intended to fit very tightly within the passageways 12 and 13 and, in fact, to have a substantially driving fit. The flanges or heads 5 18 and 19 are also pressed tightly against the tail-piece 3. Usually the tail-piece 3 with the thimbles 16 and 17 partly forced into position are placed in a press and the parts pressed firmly 10 together so that they will be arranged as shown in Fig. 2. The threaded opening 10 faces longitudinally of the tail-piece 3 in a direction away from the flushometer 1. The tubular member 21 is screwed into the opening 10 and is provided with a passageway 22 merging into an enlarged 15 chamber 23 having a valve seat 24. An elongated cap 25 is threaded on to the tubular member 21, as shown in Fig. 2, and is provided with an aperture 26 in the bottom. A wire mesh screen 27 is arranged to cover the opening 26 and immediately 20 above the wire mesh screen is a pin 28 on which the head 29 of a valve 30 normally rests. This valve is provided with flattened sides 30' so that air may readily pass around the valve when it is in open position. Preferably the valve has 25 a very loose fit in the chamber 23 so air will not only pass along the flattened parts 30' but around the entire valve. The valve 30 fits loosely in the chamber 23 and is provided with a beveled end 31, which fits against the seat 24 when the valve 30 member is raised by the pressure of water entering the opening or aperture 26. In this way the water is prevented from passing into the passageway 31 and eventually out through the passageways 20.

35 In operation normally the parts are in the position shown in Fig. 2. When the handle 32 of the flushometer is actuated a certain volume of water will quickly pass into and through the tail-piece 3 for flushing the toilet bowl 33. This volume 40 of water will produce a pressure in the tail-piece 3 and, consequently, some of the water will pass through aperture 26 and raise the valve 30 for closing the same. As soon as all the water has flowed past the vacuum breaker 2, the weight 45 of the valve 30 will cause the same to automatically move downwardly to the position shown in Fig. 3, whereby air from the room may pass into the tail-piece 3 through passageways 20, passageway 22, chamber 23, and aperture 26.

50 By means of the structure just described, no water can pass outwardly through the passageways 20, but clean air from the room may quickly pass into and fill the interior of the tail-piece 3 so that this tail-piece is always provided with 55 clean air and this clean air is renewed any time the flushometer is caused to function.

In case the water in the supply stand pipe falls 60 below the flushometer, there will be produced a certain rarefaction. This will open the flushometer 1 and immediately air in the tail-piece will flow through the flushometer into the stand pipe and fresh new air will pass in through passageways 20 and associated passageways. In this 65 way clean air is supplied through each flushometer whenever the flushometers on any floor open by reason of rarefaction in the stand pipe.

70 Instead of arranging the vacuum breaker as shown in Fig. 2 in the tail-piece 3, the vacuum breaker could be arranged in the depending portion 34 of the flushometer 1, as shown in Fig. 4. Aside from this new arrangement or new position, the structure in Fig. 4 is identical with that shown in Fig. 2 and, therefore, will need no additional description. Incidentally, it will be readily seen that easy access may be had to the

vacuum breaker whether arranged as shown in Fig. 2 or as shown in Fig. 4.

As no water passes through the vacuum breaker, it will be readily seen that it will function for many years without getting out of order as 5 nothing but clean air passes therethrough.

I claim:

1. A vacuum breaker for flushometers, comprising a supporting body having a passageway therethrough and a threaded opening intermediate the ends of the passageway, a hollow bushing snugly fitting into each end of said passageway for connecting the supporting body to a support, and a valve carried by said body adapted to move under the action of gravity to an open 10 position and under the action of water pressure to a closed position, said valve having a hollow casing open at both ends, one end being exteriorly threaded, the threaded end being screwed into said threaded opening, a gravity actuated 15 valve member loosely positioned in said casing, and means carried by the casing for supporting said valve member when spaced from its seat.

2. A vacuum breaker comprising a tubular body having a threaded outlet intermediate its 25 ends, a tubular member having one end screwed into said outlet, said tubular member having a valve seat, a valve member positioned in said tubular member and adapted when in one position to close said tubular member, means for 30 normally supporting said valve member in an open position, and tubular bushings snugly fitting into the ends of said body for securing said body to a tubular structure through which water is 35 adapted to pass.

3. A vacuum breaker comprising a tubular body having a passageway entirely therethrough and a right-angle passageway merging into the first-mentioned passageway, a pair of friction held thimbles extending into the respective ends 40 of said body for holding the body in functioning position, each of said thimbles having a passageway extending entirely therethrough, a tubular member formed with a valve seat, a valve loosely fitted in said tubular member and adapted to be 45 moved to a position against said valve seat, a cap carried by said tubular member having an aperture therein, and a pin carried by said cap for holding the valve member away from said aperture whereby when said valve member is 50 resting on said pin air may pass freely through said thimbles, said body, said tubular member and said aperture.

4. A vacuum breaker adapted to be installed in the tail-piece of a flushometer, a pair of tubular thimbles extending through the side walls of said tail-piece, a tubular body supported by said thimbles, and a valve for regulating the passage of air through said body into said tail-piece, said valve being gravity actuated.

5. A vacuum breaker including a pair of supporting hollow bushings, a tubular body having its ends snugly fitting over said bushings so as to be supported thereby, said body having a threaded aperture, a valve casing formed with a seat having one end screwed into said threaded aperture and a valve member in said casing adapted to engage said seat for closing communication between points exterior of the tubular body and points interior thereof.

6. The combination with the tail-piece of a flushometer having aligned apertures, a tubular headed thimble extending through each of said apertures to points interior of the tail-piece, a tubular body telescopically fitted over those parts

70

75

of said thimbles which project interiorly of the tail-piece, said tubular body having a right-angle outlet, a tubular member threaded into said right-angle outlet, said tubular member having a valve seat, a passageway extending from said valve seat to the interior of said body, and a chamber extending in the opposite direction, a valve arranged in said chamber formed with an end adapted to engage said valve seat, a cap

threaded on to said tubular means and extending below the same, said cap having an aperture at the end farthest from said tubular member, a screen arranged interiorly of said cap covering said aperture, and a supporting member arranged 5 interiorly of said screen, said supporting member acting to support said valve when in an open position.
